UNITED STATES PATENT OFFICE.

WILLIAM JOHN LAWRENCE, OF TORONTO, ONTARIO, CANADA.

CORE FOR USE IN THE MANUFACTURE OF WICKER AND REED BASKETS.

Application filed September 6, 1928. Serial No. 304,270.

My invention relates to improvements in cores for weaving wicker and reed baskets.

Heretofore, it has been customary to utilize cores having smooth peripheral walls, and when such cores are used by the blind 5 in weaving baskets, there is nothing to guide the operator in maintaining the upright reeds in planes intersecting the axis of the core so that as the weaver cannot see his work, it is very easy for the upright reeds 10 to become displaced with the result that the finished work may not pass examination and be condemned, whereupon it is necessary for the operator to unweave the whole basket and start his work over again.

15 It will be appreciated that this is very discouraging to the basket weaver and lowers his efficiency as an operator, besides which it materially reduces the financial returns which he obtains from his work.

20 The object of the present invention is to overcome the difficulty referred to above and to provide means whereby the operator may readily maintain the upright reeds in the proper relative position to each other and 25 the axis of the basket, with the result that the work when finished will in such respect at least pass inspection, and be in proper condition to be offered for sale.

30 I attain my object by forming the core, which may be formed in two or more transverse sections, with a plurality of guides extending lengthwise of its outer surface adapted to facilitate the accurate placing of 35 the upright reeds. One or more of the guides are preferably made distinguishable by touch from the others to indicate starting or stopping points in the placing of the upright reeds or in the weaving.

40 The invention is hereinafter more fully described and is illustrated in the accompanying drawings in which

Fig. 1 is an elevation of my improved core, with a separate end section spaced 45 apart;

Fig. 2 a fragmentary vertical section of a portion of the core shown in Fig. 1; and

Fig. 3 a plan view of the core looking 50 upwardly and showing the reed guides on the peripheral wall of the core.

Like characters of reference refer to like parts in the several figures.

Referring to the drawing, C is the body 55 of my improved core which, in the embodiment illustrated, is of frusto-conical form

having on its outer wall or periphery a plurality of upwardly extending ribs B' lying in planes in which lies the axis of the core, each of said ribs acting as a guide for an upright reed when weaving a basket. In 60 order that the starting point may be readily identified, I make one of the ribs 65 distinguishable from the others by touch and for this purpose I make it double, as shown at 10', so that the operator may by sense of touch, determine the point from which he started weaving and thus be able to judge how to proceed with his work.

Co-operating with the body portion is an 70 end portion A, which may be of frusto-conical shape and provided on its outer wall with a plurality of ribs B preferably equal in number to those on the body portion C and arranged in alignment therewith.

A double rib 11' on the end forms a continuation of the rib 10'.

The parts of the core are provided with a central hole D and with washers E. A clamping bolt F passes through the central hole and the washers and is provided with 80 thumb nut whereby the parts of the core may be held in assembled position. It is evident that the core may be built up in more than two sections according to the 85 shape of the basket to be made.

Any convenient construction of the guides may be adopted. I show them as ribs bent up from metal plates, which may be secured in any suitable manner to the core, which will usually be of wood, but may be made 90 of aluminum or any other light material.

Usually the end portion will have the part thereof adjacent the body of the same size and shape as the adjacent end of the body.

95 Preferably the body of the core is formed of two end disks connected by a central tube G, which serves as a guide for the bolt F, as, otherwise, a blind worker has difficulty in passing the bolt through holes in spaced disks.

100 What I claim as my invention is:

1. A core for manufacturing wicker and reed baskets having a substantially continuous surface and a plurality of continuous guides extending lengthwise of its outer surface adapted to facilitate and permit assurance of the accurate placing and lining up of upright reeds used in the construction of a basket.

110 2. A core substantially as set forth in

claim 1 in which the guides are formed by narrow ribs projecting from the surface of the core.

3. A core substantially as set forth in claim 1 in which one guide is so shaped as to be distinguishable by touch from the others to indicate the starting point in the weaving of the basket.

4. A core for manufacturing wicker and reed baskets comprising a body and a tapered end portion detachably connected, said end adjacent the body being of substantially the same diameter as the adjacent end of the body, both the body and end having substantially continuous surfaces and a plurality of continuous guides extending length-

wise of their outer surfaces to facilitate and permit assurance of the accurate placing and lining up of upright reeds used in the construction of a basket.

20

5. A core according to claim 1 formed of end disks connected by a plurality of metal plates having ribs bent up therefrom to form the guides.

6. A core according to claim 1 formed of end disks connected by a central tube and by a plurality of metal plates having ribs bent up therefrom to form the guides.

Signed at Toronto this 16th day of August, 1928.

WILLIAM J. LAWRENCE.
